TONE CONTROL AMPLIFIER

Pierre August Joseph Leopold Visschers, Antwerp, Belgium, assignor to International Standard Electric Corporation, New York, N. Y., a corporation of Delaware

Application January 22, 1943, Serial No. 473,274
In the Netherlands September 12, 1941

9 Claims. (Cl. 179—171)

1

This invention relates to tone controls and more particularly to tone controls for radio receivers and the like.

A principal object is to provide an improved tone control for audio frequency amplifiers employing reversed or negative feedback.

It has been proposed heretofore to provide the reversed feedback circuit of an audio frequency amplifier with circuit connections for tone control, whereby the tone control and negative feedback are combined. This prior combination controls the cutoff of the higher frequencies of the audio band when the tone control is turned in one direction but does not exercise a like effect on the higher frequencies when turned in the opposite direction.

Accordingly, one of the principal objects of the present invention, is to provide a tone control adjustment such that when it is turned in one direction it cuts off the higher frequencies and when turned in the opposite direction it produces a rising gain in the higher frequencies.

The results obtainable with this arrangement are comparable with those obtained by other but more costly and complicated means, e. g., variable selectivity controls, band-width controls and the like.

The invention is characterized by a tone control comprising a potentiometer which is connected symmetrically between and in series with a pair of condensers. One of the condensers is connected also to the control grid of a succeeding amplifier tube while the other condenser is also connected into the reversed feedback circuit for the first amplifier tube. The movable arm of the potentiometer is connected so that when it is moved towards the first-mentioned condenser, the higher frequencies in the audio band are cut off and when it is moved in the opposite direction, that is towards the second-mentioned condenser, the cutoff action is first reduced, then entirely stopped and finally reversed into a rising characteristic of the said higher frequencies.

While the invention is concerned primarily with the tone control of the audio frequency amplifier of a radio receiver, it will be understood that it is applicable to other types of amplifiers where higher and lower frequencies of a band of signal frequencies are being amplified. Furthermore, only those parts of a two-stage audio frequency amplifier are shown as are sufficient to enable the inventive concept to be understood. It will be understood of course that the invention is not

2

limited to a two-stage amplifier but can be embodied in more than two stages.

Accordingly, in the single figure of the drawing, there is shown a part of a radio receiving set, namely the audio frequency amplifier stages embodying the inventive features.

Referring to the drawing, there is shown a first amplifier stage V_1 comprising for example a triode of the indirectly heated cathode type, although as will be understood any other type of grid-controlled amplifier tube may be employed. The audio frequency signals to be amplified are impressed in the usual manner on the control grid CG_1 of tube V_1 and the cathode K is returned to ground through the biasing combination of resistor BR_1 and parallel condenser BC_1 through a negative feedback resistor R_1 . The source of heating current for the cathode heater HI is omitted from the drawing for the sake of simplicity. The second stage of the amplifier comprises for example a double grid tube V_2 which may be a so-called shield-grid tube comprising the indirectly heated cathode K_2 with its heater filament H_2 , a control-grid CG_2 , a shield-grid SG_2 and the anode plate P_2 . The signal output circuit of tube V_1 is coupled for example through the coupling resistor CR and coupling condenser CC to the control grid CG_2 in the well-known manner. Likewise, a grid leak resistor GL is connected to the grid CG_2 in the well-known manner. This grid is biassed in the customary way by means of the cathode resistor BR_2 and its parallel condenser BC_2 . The output of the tube V_2 is coupled to a suitable reproducer S by means of the coupling transformer TR , the primary of which is connected to the plate P_2 and the plate potential positive terminal HT .

A portion of the output energy from the stage V_2 is connected by the reversed feedback line L through the usual reversed feedback resistors R_1 , R_2 , to the input side of stage V_1 . However, in addition to these two conventional resistors R_1 and R_2 , another resistor R_4 is, according to the invention, connected in series in this negative feedback line. For the purpose of tone control in accordance with the present invention, the grid CG_2 and the plate P_1 are connected to a point between the resistors R_2 and R_4 through a series circuit comprising two condensers C_1 , C_2 , and the potentiometer resistance R_3 . The slider arm SL of this potentiometer is returned to ground as shown.

The condenser C_1 and the potentiometer resistance R_3 are therefore similar to those commonly used for tone control. The action of these

two elements C_1 and R_3 in the usual tone control circuit is that when the slider SL of the potentiometer is moved in one or the other direction, the effective loading of the plate circuit of tube V_1 is increased or decreased for the higher audio frequencies. In other words, when the slider SL is moved so as to connect the condenser C_1 directly to ground, the external plate impedance of tube V_1 decreases as the signal frequencies increase, because of the action of condenser C_1 which is then connected from plate to ground. When the slider SL is moved in the opposite direction, that is towards condenser C_2 , there will be a decrease in the plate loading of tube V_1 for the higher frequencies proportionally to the increase in the resistance which is now included in series with C_1 and ground. The effect of this therefore, is to reduce the cutoff effect at the higher audio frequencies. By connecting the tone control circuit in the manner shown in the drawing with a suitable proportion of values of condenser C_2 , resistances R_2 and R_4 , an additional advantage is obtained. While the usual reversed feedback circuit consists of the two resistances R_1 and R_2 , when the amplification of the two stages V_1 and V_2 is normal, the reversed feedback compensation therefor, will be approximately uniform over the entire frequency band to be covered. By the addition of R_4 and C_2 in combination with R_3 , however, this action can be modified according to the position of the slider SL and the selected values of R_4 and C_2 . These two values are selected in accordance with the maximum action obtainable from the circuit shown, where R_3 because of the fact that it is variable permits the modification of the action up to the maximum obtainable by means of the selected values of C_2 and R_4 . The action of C_2 and R_4 when the slider SL is in a position where the said slider is closer to C_2 than to C_1 is as follows. As the signal frequency increases, the impedance of C_2 decreases in proportion thereto and will therefore, in combination with R_4 , produce a voltage drop proportional to the frequency increase across R_4 of the voltage derived from the line L and which, through R_4 and R_3 , is applied to the cathode of tube V_1 across R_1 . This also reduces the amount of reversed feedback in proportion to the increase in the frequencies, and therefore increases the overall amplification of the stage V_1 for these frequencies.

Depending upon the position of the slider SL , this action will be maximum when there is no resistance left between the slider and C_2 , or will progressively decrease as the slider is moved in the other direction and the series resistance between the slider and C_2 increases. This, therefore, constitutes a means of adjusting the amount of the action of this part of the circuit. The maximum obtainable depends upon the amount of reversed feedback used.

Considering the complete working of the circuits combination it follows that by moving the slider to the side of the potentiometer connected to C_1 that higher frequencies are cut-off by the action of C_1 and, therefore, will cause reduction in the reproduction of the higher audio-frequencies. By moving the slider of the potentiometer R_3 to the other side, this cut-off action is first reduced, then, when the amount of resistance is large enough, will cease entirely. By moving the slider further to the side connected to C_2 we have the reversed action, i. e., rising for the higher frequencies, which action will increase when the amount of resistance between the slider and C_2 decreases to the minimum obtainable which is,

when the slider is in direct contact with the point of the potentiometer connected to C_2 , and this maximum action will depend upon the values of C_2 and R_4 and the amount of reversed feedback used in total.

Various changes and modifications may be made in the disclosed embodiment without departing from the spirit and scope of the invention.

What I claim is:

1. An amplifier including at least one grid-controlled audio frequency amplifier tube, a negative feedback circuit for said tube, a tone control including a pair of condensers in series between the plate of said tube and the negative feedback circuit, adjustable means movable in one direction to increase a resistance in series between one of said condensers and ground while decreasing the amount of resistance between the other condenser and ground, said tone control being connected to said negative feedback circuit whereby adjustment of said tone control simultaneously achieves the effect of variable selectivity.
2. A plural stage audio frequency amplifier comprising a first amplifier tube and a second amplifier tube coupled together for signal amplification, a negative feedback resistor connected to the input circuit of the first tube, means to apply a voltage to said resistor under control of the output of said second tube including a pair of resistors connecting the output of the second tube to the input of the first tube, a tone control circuit in the form of a T-branch connected from a point between said pair of resistors to a point in the output circuit of said first amplifier tube, said tone control circuit including in series a potentiometer resistance and a condenser connected to each end of said potentiometer resistance, the slider of said potentiometer resistance being connected to ground.
3. An amplifier including at least one electron discharge tube, a reverse feedback circuit and a shunt path connected at one end to the anode of one said tube and at the other end to a lead of the reverse feedback circuit and including a condenser connected as a plate load, a second condenser connected to said lead of the reverse feedback circuit, a potentiometric resistance connected in series between said condensers and an adjustable arm directly connected to ground, the movement of said arm along said potentiometric resistance simultaneously effecting tone control and varying the frequency characteristic of the reverse feedback current.
4. An amplifier as set forth in claim 3 in which a resistance is inserted in said reverse feedback circuit between the point of tapping the reverse feedback current and the point at which said second condenser is connected to said reverse feedback lead, the values of said resistance and of said condenser and the position of said adjustable arm determining the characteristics of the reverse feedback current.
5. An amplifier as set forth in claim 3 in which said reverse feedback circuit includes a pair of series resistances and said second condenser is connected to said reverse feedback lead at a point between said resistances.
6. In an amplifier system, a frequency-discriminating amplification control arrangement, comprising, in combination, tone control means for attenuating a predetermined band of frequencies in the signal being amplified, reverse feedback circuit means for said amplifier system, frequency-discriminating means in said feedback circuit means for reducing the reverse feedback

in said predetermined band of frequencies to increase the amplification thereof, and variable circuit means forming part of said tone control means and of said frequency-discriminating means for increasing the amount of attenuation by said tone control means of said predetermined band of frequencies when varied in one direction and for reducing the reverse feedback through said frequency-discriminating means to increase the amplification of said band of frequencies when varied in the opposite direction, whereby the amplified signal in said predetermined range of frequencies may be varied from a condition of considerable attenuation when said variable means is at one end of its control range to a condition of considerably more than normal amplification when said variable means is at the other end of its control range.

7. In an amplifier system, a frequency-discriminating amplification control arrangement, comprising, in combination, tone control means for attenuating a predetermined band of frequencies in the signal being amplified comprising a condenser and a resistor in series shunting the signal path in the amplifier system, reverse feedback circuit means for said amplifier system, and a frequency discriminating circuit comprising said resistor and a second condenser in series shunted across said feedback circuit means for reducing the reverse feedback in said predetermined band of frequencies to increase the amplification thereof, said resistor being variable to increase the amount of attenuation by said tone control means of said predetermined band of frequencies when varied in one direction and to reduce the reverse feedback through said frequency-discriminating circuit to increase the amplification of said band of frequencies when varied in the opposite direction, whereby the amplified signal in said predetermined range of frequencies may be varied from a condition of considerable attenuation when said variable resistor is at one end of its control range to a condition of considerably more than normal amplification when said variable resistor is at the other end of its control range.

8. In an amplifier system including an electron discharge tube, a frequency-discriminating amplification control arrangement, comprising, in combination, a tone-control circuit shunting the tube plate circuit to ground for attenuating a predetermined band of frequencies in the signal being amplified comprising a first condenser and

resistor connected in series and shunting the signal path in the amplifying system, reverse feedback circuit means for said amplifier system, and frequency-discriminating means in said feedback circuit means and including said resistor and a second condenser connected in series and shunting said feedback circuit for reducing the reverse feedback in said predetermined band of frequencies to increase the amplification thereof, said resistor being a potentiometer with its variable contact connected to ground for increasing the amount of attenuation by said tone control means of said predetermined band of frequencies when varied in one direction and for reducing the reverse feedback through said frequency-discriminating means to increase the amplification of said band of frequencies when varied in the opposite direction, whereby the amplified signal in said predetermined range of frequencies may be varied from a condition of considerable attenuation when said potentiometer is at one end of its control range to a condition of considerably more than normal amplification when said potentiometer is at the other end of its control range.

9. An amplifier system as described in claim 8 wherein said resistor is a potentiometer having a sliding contact connected to ground and said first condenser is connected between one end of said potentiometer and the plate of said tube, and said second condenser is connected between the other end of said potentiometer and an intermediate point in said feedback circuit, said intermediate point in said feedback circuit constituting the juncture between two resistors connected in series from the output of the amplifier system to ground, the feedback voltage being developed across the grounded resistor.
